UNITED STATES PATENT OFFICE.

ARTHUR SAMUEL PIERSON, OF MORRISTOWN, NEW JERSEY.

REINFORCING AND TENSION DEVICE FOR CONCRETE STRUCTURES.

No. 880,820.

Specification of Letters Patent.

Patented March 3, 1908.

Application filed December 8, 1905. Serial No. 290,930.

To all whom it may concern:

Be it known that I, ARTHUR SAMUEL PIERSON, a citizen of the United States, and residing at Morristown, in the county of Morris and State of New Jersey, have invented certain new and useful Improvements in Reinforcing and Tension Devices for Concrete Structures, of which the following is a specification, such as will enable those skilled in the art to which it appertains to make and use the same.

This invention relates to what are known as fireproof structures or buildings, and particularly buildings of this class which employ columns, beams, girders and the like, and floor and ceiling construction, composed of concrete reinforced with steel bars, ties, expanded metal, or other devices of various kinds and classes which are embedded in the concrete material, and the object of the invention is to provide an improved reinforcing or strengthening device for use in structures of the class specified, and which may be employed as a reinforcing and tension device in all forms of concrete fireproof structures, and in the making of slabs or plates of concrete material of any size.

The invention is an improvement on that described and claimed in an application for Letters Patent of the United States filed by me March 17, 1905, Serial No. 250,571, and is fully disclosed in the following specification of which the accompanying drawing forms a part, in which the separate parts of my improvement are designated by suitable reference characters, in each of the views, and in which:

Figure 1 is a sectional side view of a reinforcing device of the class specified made according to my invention; Fig. 2 a transverse section on the line 2—2 of Fig. 1; and, Fig. 3 a view similar to Fig. 2 but showing a modification.

In the practice of my invention as shown in the drawing I provide a strip *a* of what is known as expanded metal, said expanded metal being the same as that employed by what is known as the "Expanded Metal Engineering Company of New York" and consisting of a sheet of steel or similar material which is cut longitudinally and at regular intervals to form parallel slits or slots which are alternately arranged in adjacent lines, the sheet or strip after being so cut being expanded or drawn out laterally so as to form diamond or similarly shaped openings *a*², in-

closed by diagonally arranged bars *a*³ which cross each other in opposite directions, the opposite edges of the strip or sheet when so expanded being provided with projecting loop members *a*⁴.

In the practice of my invention I connect with the strip or sheet of expanded metal made in the manner above described, parallel side bars *b* composed of strips of metal bent or folded longitudinally in such manner that they are U-shaped in cross section, and in practice the opposite edges of the expanded metal strip are inserted into said bars, or between the separate sides thereof, and secured therein in such manner that the bars *b* form substantially an integral part of the device, and the strips of expanded metal cannot be forced together laterally, and the strength thereof is largely increased, and in this way I am enabled to employ the device thus formed as a reinforcing and tensional device for bars, beams, girders, and all similar forms of construction made of concrete, and also in floor and ceiling constructions, and in ties of various kinds and classes and in slabs for various purposes.

My improvement particularly adapt the use of the expanded metal described to the formation of girders, beams and other articles which necessitate the placing of the reinforcing and tension device on edge so as to add strength and resistance to beams, girders and other devices made of concrete material.

In Figs. 1 and 2 of the accompanying drawing the expanded metal strip is connected with the bars *b*, or said bars are secured to the expanded metal strip, by compressing parts of the sides *b*² of said bars into the spaces between the loop members *a*⁴ and into the space within said loop members as clearly shown at *b*⁵ in Fig. 1 and as also shown in Fig. 2, and in the construction shown in Fig. 3, in addition to compressing the sides *b*² of the bars *b* into the spaces formed by the loop members *a*⁴ to cause the said bars to firmly clasp or partially embrace the said loop members and hold them and the strip firmly in their expanded condition, I also connect the sides opposite said loop members and within the same by rivets *c*, and the construction shown in Fig. 3 gives strength, as will be understood, to the reinforcing or tension device, and with this construction it will be apparent that the bars *b* cannot be forced together without breaking

the expanded metal or metal sheet, or without breaking the bars *b*.

My invention is not limited to the exact form of the bars *b* nor to the exact means 5 herein shown and described for connecting said bars with the strip of expanded metal, and other forms of construction may be employed for this purpose; and although I have shown and described a strip of expanded 10 metal made in a particular manner, it will be apparent that expanded metal formed in other ways may be substituted for that herein described.

Having fully described my invention, what 15 I claim as new and desire to secure by Letters Patent, is:

1. A reinforcing device for use in concrete structures, comprising a strip or sheet of expanded open work metal having loops or projections at its opposite sides and parallel side 20 bars of sheet metal firmly clasped upon the looped sides of said strip or sheet, portions of said side bars passing partially around, or partially embracing the material of said 25 loops and holding the said loops and the said sheet rigidly in their expanded condition, substantially as described.

2. A reinforcing device for concrete structures, comprising a strip or sheet of expanded open work metal having loops or 30 projections at its opposite sides, and parallel side bars U-shaped in cross section, said side bars being firmly clasped to said strip or sheet, by having the metal of said side bars compressed upon and about said loops 35 or projections, substantially as described.

3. A reinforcing device for use in concrete structures, comprising a strip or sheet of expanded open work metal having loops or projections at its opposite side edges, and 40 parallel side bars U-shaped in cross section, the said loops or projections extending between the sides of the said side bars and having the said sides compressed firmly together within and against the said loops, 45 substantially as described.

In testimony that I claim the foregoing as my invention I have signed my name in presence of the subscribing witnesses this 6th day of Dec., 1905.

ARTHUR SAMUEL PIERSON.
